UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, N. Y., A CORPORATION OF NEW YORK.

COVER FOR LOOSE-LEAF BINDERS.

Application filed June 30, 1921. Serial No. 481,518.

To all whom it may concern:

Be it known that I, CLARENCE D. TRUSSELL, a citizen of the United States of America, residing in Poughkeepsie, in the county 5 of Dutchess and State of New York, have invented certain new and useful Improvements in Covers for Loose-Leaf Binders, of which the following is a specification.

In my Patent No. 959,182, dated May 24, 10 1910, is set forth a construction of cover for a temporary binder or loose-leaf book comprising a double binding strip extending along the book back, with the stiffening boards of the cover sides cemented between 15 the edge portions of the two layers of such binding strip. The metal back plate or binding plate, by which the loose-leaf binding device is attached to the cover, is confined between such double binding strip and 20 the book back, the latter being a layer of outer covering fabric (leather or textile material) comprising the exterior of the sides and back of the cover.

In my Patent No. 1,369,309, dated February 25 22, 1921, is set forth a construction of book cover for such loose-leaf binder comprising a binding strip of suitable fabric united by parallel rows of stitching to the side portions of the back of the book cover, 30 the space between the rows of stitching forming a pocket for receiving the binding plate. This construction was designed more particularly for book covers formed of an integral piece or sheet of leather or other 35 suitable fabric.

The present invention is designed to improve the construction of covers having stiff sides and a flexible back. The thick stiffening boards for the sides are united by a back 40 portion which is flexible except for the stiffness incident to the confining within it of the usual curved binding plate for attaching the temporary binding device. A double binding strip is employed, somewhat as in 45 my Patent No. 959,182, but the two layers thereof are united by parallel rows of stitching adjacent to the outer edges of the binding plate and within the inner edges of the stiffening boards. The flaps or layers of 50 the double binding strip receive the stiffening boards between them, joining the latter substantially in the plane of their exterior faces, so as to leave the thickness of the boards projecting inside of the back. In-

stead of cementing the binding plate fast to 55 the back of the cover, a fabric pad is introduced between them, being cemented to the back. Thus is formed between such pad and the outer layer of the double binding strip a pocket for receiving the curved binding plate; the latter is preferably uncemented to the fabrics on either side. The binding plate emerges from this pocket near the opposite ends of the book back, and is provided with any usual means for clamping or otherwise uniting it to the back plate of the binding mechanism.

The general nature of the invention being thus indicated, I will proceed to describe it more in detail with reference to the accompanying drawings, wherein—

Figure 1 is a perspective view of a ring binder the cover of which is constructed according to the present invention, lying open;

Fig. 2 is a transverse section thereof, the 75 thicknesses of the several layers being somewhat exaggerated;

Fig. 3 is a fragmentary transverse section showing the book closed;

Fig. 4 is a face view, and

Fig. 5 a transverse section of the double binding strip;

Fig. 6 is a partially dissected view showing the construction of the cover before applying the metal parts;

Fig. 6a shows the lower portion of Fig. 6, 85 with the addition of the metal binding plate;

Fig. 7 is a view similar to Fig. 6, showing a different construction.

Fig. 8 is a transverse section answering to 90 Fig. 5 and showing a modification of the binding strip.

In Figs. 1 and 3, A shows the cover as a whole, and B indicates the binding mechanism as a whole. The latter is shown as of 95 the well-known ring binder type comprising two or more half-rings or hooks of wire which open to receive the punched sheets or leaves, and close together to confine them, the half-rings being mounted on plates or other suitable metallic foundations, the whole metallic structure being fastened to the back portion of the cover. Suitable examples of such ring binders are shown in my Patent No. 1,147,157, June 1, 1915, or in 100 No. 1,194,684, August 15, 1916; it being understood, however, that any known construction of binders of this general type may 105

be provided. Such binding devices assembled and ready to be applied to the covers, are known in the trade as "metals," as distinguished from the book cover to which 5 they are applied.

The usual means for applying the binding devices or metals to the back of the book cover comprises a curved binding plate of metal suitably united to the back portion 10 of the cover and having a clinched or other engagement with some part of the metal structure, usually a curved back plate thereof; the usual connection consists of ears or prongs turned up from the ends of the binding 15 plate, entering notches in the ends of the back plate of the binding devices and clinched down tightly upon the ends of said plate. However, other connecting means may be employed, so far as concerns the 20 present invention.

The cover A comprises stiff sides *a a*, and a more or less flexible back *b*. The sides are stiffened by means of stiffening boards *c c*, an outer cover fabric *d* being glued to the 25 outer faces of these boards, its portion between the boards constituting the outer member of the back *b*. The edges of the boards are covered by folding the outer fabric *d* around them at top, bottom, and the 30 outer sides. The inner faces of the boards are covered and concealed by pasting a lining fabric *e* of paper or woven material over them. So far as described, the construction is that usually adopted.

According to the present invention there is incorporated in the back portion of the cover a double binding strip *C* shown separately in Figs. 4 and 5. This is made of two layers of suitably strong woven fabric 40 cut to equal or similar width, and united longitudinally by parallel rows of stitching *f f*, *g g*. The rows *f f* are spaced apart a distance about equal to the width of the metal binding plate to be used. This plate 45 is shown at *D* in Fig. 2. The rows of stitching *g g* are extended somewhat close to the rows *f f*. The distance between the rows *g g* is slightly less (measured around the curve of the back) than the destined spacing 50 of the inner edges of the boards *c c*. Outside of the rows of stitching the two layers of the binding strip form flaps *h h'*, between which each of the boards *c* is to be received. The flaps *h'* are turned up as shown 55 in Fig. 4, and the approaching faces of the flaps covered with glue; the boards are then inserted between them at the proper spacing, lying substantially flat on the lower flaps *h*; the upper flaps are carried up against 60 the inner edges of the boards, as shown at *i* in Fig. 2, and laid down flat on the upper faces of the boards. There results a sort of flexible hinge which is nearly aligned 65 with the outer faces of the boards. A strip of fabric of substantially the width and

length of the book back, which I will call the "pad," and which is shown at *j*, is applied against the inner face of the outer covering fabric *d*. A convenient way is to attach this temporarily to the outer face of 70 the binding strip *C* by tips or points of adhesive such as can easily be broken away afterward. The outer covering fabric *d* having been cut to the proper size, and its inner surface coated with glue, the binding strip and attached cover members are laid thereon and the respective parts pressed together. This cements the pad *j* to the back portion of the cover fabric, and cements the boards and flaps *h* to the side portions of 75 such fabric, leaving the edges of the latter projecting, as shown in Figs. 6 or 7. These projecting edge portions are then turned in around the outer edges of the boards in the well known manner. The cover is finished 80 by applying the linings *e e* on the sides as usual.

The described construction affords a pocket between the outer layer of the binding strip *C* and the inner surface of the 90 pad *J*, of a width approximating the space between the rows of stitching *f f*. Into this pocket the metal binding plate *D* is to be introduced. The temporary tips of adhesive 95 easily break away while introducing this plate. The opposite ends of the plate emerge from this pocket for attachment to the back plate of the binding mechanism. Two constructions are within the invention.

1. The construction shown in Fig. 6 is characterized by extending the binding strip *C* for substantially the whole length of the book back and cutting slots *k* preferably through both layers of the binding strip, 105 through which slots the metal plate is introduced, the pocket for this plate being the portion between the two slots. The end of the metal plate *D* projects through the slot *k* as shown in Fig. 6^a. Preferably the outer layer of the binding strip is carried beyond the boards, as shown at the upper part of Fig. 6, forming a reinforcing layer *m* which becomes glued to the covering layer *d*, and, in the turning in of that layer, serves to stiffen the end portions of the 110 book back *b* and thereby render the book back more durable at its top and bottom ends. With this construction the pad *j* may very well be of a length equal to the length 115 of the boards *c*.

2. Referring to the construction shown in Fig. 7, the binding strip *C* has a length only equal to that of the pocket for confining the metal binding plate (that is, a length equal to that between the slots *k k* in Fig. 6). To provide the stiffening for the book back, which in Fig. 6 is afforded by the extended portions *m*, the pad *j* is extended beyond the boards *c* at both top and bottom, as shown in the upper part of Fig. 7; so that 120

when the outer marginal portions of the covering fabric *d* are turned in upon the edge portions of the boards, this additional length of the pad serves as a reinforce for 5 affording added stiffness to the top and bottom ends of the book back *b*. This construction affords greater flexibility along the hinge joint between the sides and back than that shown in Fig. 6, but is not so strong. 10 For some constructions and sizes of loose leaf books the one construction may be preferred, and for others the other construction may be preferable.

The construction provided by this invention has certain important advantages as compared with those heretofore used for loose-leaf books having covers. The flexible hinge connection between the back and sides comprises three layers of fabric, which affords 15 a much stronger hinge connection than heretofore. This connection, while increased in strength, is not stiffened or diminished in suppleness. Its strength is such that if the outer covering layer (which usually affords 20 the only connection between the back and sides) were cut away or worn through, the hinge joint would still be amply strong, and the binder could continue in use for a long time. When the book is closed (as shown 25 in Fig. 3) the portion *i* of fabric covering the inner edges of the boards is folded down against the stitched portion, so that three layers of fabric intervene between the inner edge of the board and the edge of the plate 30 *D*. This brings the outer edges of the plate *D* into line with the edges of the board, drawing the outer fabric of the book back snug against the plate *D* and giving a symmetrically rounded back with a firm, rigid, 35 and exceedingly strong binding connection. In this respect the cover is greatly superior to those heretofore used, where the edges of the binding plate *D* are between the sides of the covers when the latter are closed, 40 which leaves the covering fabric loose on the back and affords a less secure hinge connection. Another advantage is that the pad *j* adds to the life of the book back, as the covering fabric will wear better, because of 45 having a soft substance next to it, than if stretched, as heretofore, directly over the hard steel plate. The presence of the pad also serves to avoid the gluing of the book back to the binding strip, and thus leaves 50 between them the pocket for inserting the binding plate. In most previous constructions of loose leaf books, the covering fabric has been glued fast to the binding plate, but as it is impossible to satisfactorily glue cloth 55 or other covering fabric to metal, this attachment soon gives way and permits the back to wrinkle, a defect which is avoided by the present construction. Another desirable feature is that since the hinge joint 60 is carried close to the outer faces of the

boards, and the latter are not beveled or chamfered off on their edges approaching the book back, the entire thickness of the sides of the book is availed of to lift the sheets or leaves to be bound to a higher position than heretofore upon the curved top plate usually employed as the upper member of the binding structure from which the hooks project; so that the sheets to be bound lie flat when the book is open, instead of having a hump by reason of their bound edges being tipped upwardly where they are lifted onto this top plate. 70

The invention lends itself readily to facilitating quantity production. For each width of ring binder (metals) the binding strip *C* may be made up in great lengths by stitching the two layers together with the four parallel rows of stitching. Then for each lot of covers of a given size, these prepared strips are cut across into lengths corresponding with the length of the book cover to be made. In assembling the boards and strips, the lines of stitching serve as a guide for determining the proper spacing apart of the 80 boards. 85

While the construction thus described in detail is preferred, yet it is to be understood that the invention is not limited to all the details set forth, but may be modified within the scope of the appended claims. For example, the construction is applicable to what are known as half-bound or quarter-bound books, as well as full-bound books. It is only in full-bound books that the outer cover fabric need cover the entire outer faces of the boards and be turned in all around their outer margins. This outer cover fabric may be any suitable woven fabric or any other material of sufficient flexibility or durability, such as leather or its substitutes. It is preferable to employ a double binding strip *C*, yet the invention may be partly availed of with a single binding strip or a binding strip which is only partly double. These modifications are shown in Fig. 8, where *C'* is a single binding strip of suitably heavy material, and *q q* are auxiliary strips of like material stitched thereto at *g g* and glued to the inner edges and surfaces of the boards, 90 their function being mainly to give an attractive finish, although serving partly the function of the flaps *h* of the binding strip *C*, according to the preferred construction. 95

One important advantage of the present invention is that it provides for the first time a loose-leaf book which admits of being lettered on the back without injury; that is to say, the customer buying this book from a stationer can take it to a book-binder or printer and have any desired title or lettering applied on the back without any injury to the book. This is due to the fact that the book back is drawn tightly over the binding plate, since the edges of the cover boards 100 105 110 115 120 125 130

have a bearing upon the edges of this plate, and the plate occupies substantially the entire width of the book, so that as the covers are closed, the covering fabric is stretched 5 snugly over the back of the book, and the binding plate affords a firm foundation for receiving the pressure due to printing; whereas with ordinary constructions of loose-leaf binders, where the back is held 10 loosely, it is necessary to open out the cover, placing the rings downward, and improvise a base to support the metals, in order to sustain the pressure incident to printing or stamping the lettering, which comes entirely 15 against the ring metals and not against the back plate, and which, unless great precautions are taken, is almost certain to injure the mechanism.

The use of the lining pad *j* greatly economizes in the cost of producing the cover, 20 since it enables the outer covering fabric to be expeditiously coated by running it through a gluing machine, thereby applying a uniform coating of adhesive to its entire 25 surface, after which the portion of this surface destined to become the back of the book is covered by applying the lining pad thereto.

I claim as my invention:

30 1. A cover for a loose-leaf book comprising side boards, an outer cover fabric, a binding strip united to the boards, a loose-leaf binding device, and a binding plate on which said device is mounted, attached to the 35 intervening back portion of the binding strip, and located with its edges beneath the edges of the boards when the book is closed.

2. A cover for a loose-leaf book comprising side boards, an outer cover fabric, a binding strip united to the boards, a loose-leaf binding device, and a binding plate on which said device is mounted, attached to the intervening back portion of the binding strip, the hinge flexure being closer to the 45 outer edges than the inner edges of the boards so that when the book is closed the edges of the boards fold in over the edges of the binding plate.

3. A cover for a loose-leaf book comprising side boards, an outer cover fabric, a binding strip united to the boards, and a binding plate confined in the space between the intervening back portion of the binding strip and said cover fabric, the hinge flexure 55 of the cover fabric and binding strip being so close to the outer edges of the boards that when the book is closed the boards fold in over the edges of the binding plate, so that the thickness of the boards lies at least 60 partly between the outer edges of the binding plate.

4. A cover according to claim 2, the binding strip being double, forming two marginal flaps at each side, between which the 65 boards are cemented.

5. A cover according to claim 1, the binding strip being double, and its layers united by parallel rows of stitching.

6. A cover according to claim 5, the layers of the binding strip united by double 70 rows of stitching on opposite sides.

7. A cover according to claim 4, the outer flaps cemented against the outer surfaces of the boards and the inner flaps cemented against the inner edges and inner surfaces 75 of the boards.

8. A cover for a loose-leaf book, comprising side boards, an outer cover fabric, and a binding strip, forming sides with an intervening back, the book back being 80 formed, between the outer cover fabric and the binding strip, with a pocket for receiving the binding plate of the loose-leaf binding device, and the side boards hinged to fold inward as the book is closed, so that 85 their thicknesses lie partly within the width of the binding plate.

9. A cover according to claim 1, with a pad lining the back of the cover fabric, a pocket for the binding plate being formed 90 between such pad and the binding strip.

10. A cover for a loose-leaf book comprising side boards, an outer cover fabric, a double binding strip the layers of which are 95 united by parallel rows of stitching, their flaps beyond the stitching receiving the boards between them and cemented thereto, and engaging the boards adjacent the outer faces thereof, and the binding plate of a loose-leaf binding device applied between 100 the binding strip and cover fabric, whereby, when the book is closed, three layers of the binding strip fabric are interposed between the edges of said binding plate and the inner edges of the boards.

11. In a loose-leaf book, a cover comprising side boards, an outer cover fabric, and a binding strip united to the boards, a soft flexible pad lining the back of the cover fabric, and a loose-leaf binding device having 110 a rigid metal binding plate, the latter introduced at the back between the binding strip and lining pad and unattached to either.

12. A cover for a loose-leaf book comprising side boards, an outer cover fabric and a binding strip, forming sides and an intervening back, having the ends of the book back reinforced by a layer of fabric folded in with the cover fabric.

13. A cover according to claim 1, in which the binding strip is extended at its ends beyond the ends of the boards, and folded over to strengthen and reinforce the book back at its ends.

14. A cover according to claim 11, the pad extended at its ends beyond the boards, and such extended portion folded in to reinforce the ends of the book back.

15. A cover comprising boards, a binding 130

plate and a double binding strip extending from end to end of the boards, and formed with slots through which the ends of the binding plate project.

5 16. A cover for loose-leaf books comprising side boards, and an intervening flexible back, combined with a binding plate confined against said back, with its edges underlying the edges of said boards when the

10 book is closed.

17. A cover for loose-leaf books comprising side boards, a cover fabric, and a binding strip attached to the outer sides of the boards, with a binding plate secured outside of the binding strip, the binding strip forming a flexible hinge connection with the boards near their outer faces, so that the boards fold in above the edges of said plate when the book is closed.

15 18. The method of forming a cover consisting in stitching together two layers of binding fabric to form a double binding strip by rows of parallel stitching, cutting

such strip into suitable lengths, applying cement to the flaps thereof beyond such 25 stitching, laying stiffening boards between said flaps upon the lower flap and closely adjacent the outer rows of stitching, extending the inner flap up against the inner edges of said boards and out over the inner faces 30 thereof, applying these assembled elements upon a layer of outer cover fabric coated with cementing material, pressing the parts together, and closing the projecting edges of the 35 cover fabric over the outer edges of the boards.

19. A method according to claim 18, with the addition of a pad applied to the back portion of the cover between the binding strip and outer cover fabric, and cemented 40 to the latter, whereby to form an uncemented pocket between such pad and the binding strip for receiving a binding plate.

In witness whereof, I have hereunto signed my name.

CLARENCE D. TRUSSELL.
